TRIP DEVICE FOR PRINTING-PRESSES.

1,116,755.

Specification of Letters Patent. Patented Nov. 10, 1914.

Application filed October 26, 1912. Serial No. 727,870.

To all whom it may concern:

Be it known that I, WARD B. STORY, a citizen of the United States, residing in the borough of Brooklyn, county of Kings, city and State of New York, have invented a certain new and useful Trip Device for Printing-PresSES, of which the following is a specification:

This invention relates to automatic devices for separating the impression cylinder and type cylinder of the printing couple in sheet printing presses, in the event that the sheets are not properly fed to the couple, or in the event that the feed for any reason is arrested. This separation of the cylinders is necessary when a sheet is not fed to the couple, as otherwise the inked type would print upon the blanket of the impression cylinder, producing a smudge upon the next sheets fed to the couple. In many sheet printing presses, the impression cylinder weighs as much as half a ton, and revolves as fast as one hundred turns a minute.

According to my invention, I seek to separate the cylinders, by moving the impression cylinder out of contact with the type cylinder, when, for any reason, the sheets are not properly fed to the couple; this mechanism to work with certainty, and to separate the cylinders with precision, and without shock or jar, and to keep them separated until the parts are adjusted to properly feed the sheets, whereupon, the two cylinders may be brought into engagement, automatically, and at the same time positively, and without altering the sequence of operation of the various parts of the apparatus. These and further objects will more fully appear from the following specification and accompanying drawings, considered together or separately:

In the drawings: Figure 1 is a diagrammatical view of certain portions of the device, showing the drop roller, the feeding tapes, and the type and impression rollers. Fig. 2 is a side view of the complete apparatus. Fig. 3 is a sectional view, taken on the line 3—3 of Fig. 2, looking in the direction of the arrow. Fig. 4 is a detail section, on the line 4—4 of Fig. 2, looking in the direction of the arrow. Fig. 5 is a detail section, on an enlarged scale, taken on the line 5—5 of Fig. 2. Fig. 6 is a detail section on the line 6—6 of Fig. 5. Fig. 7 is a similar view, taken on the line 7—7 of

Fig. 5. Fig. 8 is a side view of the anchor member of the Geneva stop movement, shown in Fig. 7. Figs. 9 to 12 are views of the tripping mechanism in different positions, Fig. 9 showing the parts during the final movement of tripping; Fig. 10 in complete tripped position; Fig. 11 in position ready to be tripped, and Fig. 12 in normal position.

I have illustrated my invention in connection with a printing press having the usual printing couple, together with improved sheet feeding devices, which, together with alining and adjusting devices, are described in certain co-pending applications for patent which will be identified, by filing date and serial number, in the following description where they occur. It is, of course, to be understood that such devices are described and illustrated solely for the purpose of making clear the principles of the invention, which is not limited in any way to the precise devices illustrated or described.

To the right of Fig. 2 is the magnetic device (shown in my co-pending application for patent, filed June 20, 1912, and numbered serially 704,707) which trips the drop rollers when the sheet buckles. If the sheet does not buckle, or if there is no sheet in the machine at that point, the "trip rod" (so designated in Fig. 2) will not be moved. This "trip rod" actuates mechanism which prevents the impression cylinder from being raised away from the type cylinder. When the "trip rod" does not move, this mechanism is brought into action, and the impression cylinder is moved away from the type cylinder. Next to the left, at the end of the "table" is the mechanism for making side register, described in my co-pending application Serial No. 688,805, filed April 5, 1912. This mechanism has nothing to do with the present case, but it is illustrated to show where it is placed upon the complete machine. It is actuated by a crank on the "cam shaft" shown in Fig. 1.

The "cam" so designated in Fig. 1, actuated the "tapes" and "gage" in the manner shown in my co-pending application for patent filed March 12, 1912, and numbered serially 683,331, and serves to retard and accelerate the movement of the tapes. The sheets are fed, by the usual tapes or belts (not shown) along the table *a*, to the feed

roller *b* and drop roller *c*, to the "gage", so marked in Fig. 1. The gage at this moment is at a point between the drop rollers *c* and *e*. The tapes being retarded, by the mechanism actuated by the cam in Fig. 1, will cause the front edge of the sheet to be arrested, which will buckle the sheet upward in contact with the front end of the lever *g*. This will depress the rear end of the lever 10 and complete the electric circuit *h*, energizing the magnet *i*. This will attract the armature, on the lever *j*, and release the latch *k*, which will be retracted by the spring *m*. The latch will be reset by means of the cam 15 *n* acting on the roller, which is located on one end of the lever *l*. The effect of this operation is that the latch *k* is released every time a sheet passes through the machine. In the event that the feeder becomes 20 empty, or a sheet becomes caught in the machine, the latch will not be sprung, because there will be no sheet to buckle and raise the finger *g*. This intermittent releasing of the latch *k* and movement of the lever *j* is utilized to actuate the mechanism which controls the movement of the impression cylinder. Before describing that mechanism, certain of the devices which are 25 shown diagrammatically in Fig. 1 and in some detail in Fig. 2, will be described. As 30 shown in Fig. 1, the straightened sheet is fed forward against the gage, by means of the "tapes", and the feed roller *d* and drop roller *e*, along the "table" and under the 35 "drop roller", shown in about the middle of Fig. 2. All of these devices are the same as disclosed in my co-pending application for patent filed June 20, 1912, Serial No. 704,707. 40 The "cam" shown in Fig. 1 actuates the belt accelerating and retarding mechanism, as in my co-pending application for patent filed March 12, 1912, Serial No. 683,331, while the sector *o* actuates the mechanism 45 which moves the drop roller sidewise as described in the before referred to application, Serial No. 688,805. The properly alined and spaced sheet is then fed to the printing couple in the usual manner, such couple comprising the "type" and "impression" cylinders (Fig. 1) and from thence it is taken by the "transfer" cylinder to the piler, or other device, such for example as that 50 shown in my application for patent filed April 22, 1913, Serial No. 762,784. It is to be understood that the drop rollers, tapes, gages and buckle-actuated fingers are duplicated, for the two side edges of the sheet, so that any irregularity in feeding the two side 55 edges will be corrected. The devices about to be described are intended to be actuated by one of these magnetic devices only, for the reason that if an irregularity occurs, which prevents the sheets from being fed, 60 or if no sheets are fed, the latch *j* will not be released, nor will the lever *k* be moved. Neither will the lever *k* be moved if only one edge of the sheet is properly alined. If one edge be properly alined while the other edge is not, it will result in a dislocated sheet, which will arrest the alining devices, and thereby prevent the moving of the trip rod, by the passage of the next sheet, which will be in sufficient time to prevent injury to the machine. The precedingly described 70 devices form no portion of the present invention, and are introduced solely for the purpose of making clear the mode of operation of the tripping devices, it being understood that for the purpose of this invention, any form of alining or gaging devices may be employed. 75 Referring now to the drawings, I will describe the mechanism which is controlled by the movement of the lever *k*: The lever *k* is connected to the trip rod 1, and moves the latter to the right, as each sheet passes through the machine. This trip rod is connected to a lever 2, which is pivoted to the shaft 3. The other limb of the lever 2 carries a roller 4, which projects to one side. This roller constitutes a movable stop, for controlling the trip devices about to be described. The cam shaft 5, has been before referred to in connection with the description of Fig. 1. On this shaft is a cam 6, which engages with a roller carried on a forked rod 7. This rod is connected to a bell crank lever 8, which is carried upon the shaft 3. The other limb of the bell crank lever is connected to a second bell crank lever 10. This latter bell crank lever is pivoted to a stub shaft 11, carried by the frame 12 of the machine. The other limb of the bell crank lever 10 carries a stop 13, which projects from one side thereof. The up and down movement of the rod 9, in response to the rotation of the shaft 5, oscillates the bell crank lever 10 upon its axis. The shaft 5 makes one revolution for each sheet that is printed, and its movement is synchronous with that of the type cylinder, impression cylinder and transfer cylinder. It is, therefore, apparent that the movement of the trip rod 1, and the bell crank 10, are synchronous, *i. e.*—each moves once for every sheet fed forward. The next element of the machine is the connection between the bell crank 10 and the stop 4. This mechanism makes effective or abortive the movement of the bell crank lever, and determines whether or not the impression cylinder is to be lifted away from the type cylinder. This mechanism is as follows: On the stub shaft 11, and close against the bell crank 10, is a lever 14. This lever has a hub 15, with a rounded exterior. Against this hub bears the crotch of a three-armed lever 16. The arms 17, 17^a, straddle the hub 15, and are held against rollers, 23, 23^a, about to be described, by the springs 18, 80 85 90 95 100 105 110 115 120 125 130

which are attracted to a pillar 19, on the frame. The third arm 20, of the lever 16, is connected to a dog 21. This dog is pivoted to a sector 22, which, in turn, is supported upon the stub shaft 11. The free end of the dog is adapted to be engaged by the stop 13, when the latter is moved upward, provided the dog is in proper position to be engaged thereby. The proper time for moving this dog occurs only when the trip rod 1 is not moved. When it is moved, the dog is not engaged by the stop. The means for securing this operation is as follows: On the stub shaft 11 is the lever 14, before described, free to rotate thereon. This lever carries two rollers, 23, 23^a, (before referred to) which are adapted to be engaged by shoulders on the inside of the arms 17, 17^a, respectively, of the lever 16, as previously described.

The springs 18 normally engage these shoulders with the rollers. The parts are so proportioned that the shoulders may engage with the rollers at the same time, provided the lever 16 is not swung to one side, in relation to the lever 14. The springs 18 will, therefore, properly support the lever 16. The lower edge of the lever 14 is enlarged along circular lines, and is toothed, forming a sector 14^a, as shown. These teeth engage with a toothed sector 24, mounted on a shaft 25. On this shaft is a bell crank lever 26, adapted to be turned by the shaft 25. One limb of the bell crank lever 26 carries a plate 27, adapted to be engaged by the roller stop 4, if the latter is in position to be so engaged. The other limb of the lever 26 is engaged by a rod 28. This rod is mounted in a bracket 29, on which it is free to slide, and the saddle is mounted on the stub shaft 11, and is free to turn thereon, to follow the angular change of direction caused by the movement of the lever 26. A spring 30, surrounds the rod 28, and exerts a downward stress thereon by engaging with the saddle and a stop 30^a on the rod. The tendency of this spring is to depress the bell crank lever 26 on one side or the other of the shaft 25, as depends upon the position that it is in.

The operation of so much of the mechanism as has been described is as follows, it being understood that the lever 10 is being oscillated synchronously with the lever 2, and the rod 9: The lever 2 is oscillated from right to left, in time with the up and down movement of the rod 9. This is shown in Fig. 12. The vertical movement of the rod 9 results in a vertical oscillation of the bell crank lever 10. At the same time, the lever 2 is moved to the left, moving the stop 4 also to the left. The spring 30 will depress the rod 28, and the movement of this rod will oscillate the bell crank lever 26, keeping the plate 27 in contact with the stop 4. As the shaft 5 rotates, the cam 6 will elevate the rods 7 and 9, and turn the bell crank lever 10 with the stop 13. At the same time, the lever 2 will be moving to the right, and the plate 27 pressing upon the stop 4, will turn the sector 24 and lever 14. This will have the effect of moving the lever 16, by engagement of the roller 23^a with the shoulder on the limb 17^a. This will elevate the limb 20 of the lever 16, which will turn the dog 21 upon its pivot, raising the free end of the dog so that the stop 13, which is now being elevated, will clear the dog, hence the rod 9 may be elevated to its full limit of travel, and with it the lever 10, without in any way moving the sector 22. This alternate movement of the lever 2 from right to left and of the rod 9 up and down, continues so long as the sheets are being fed properly and the trip rod 1 is moved from right to left. As soon as an abnormal condition occurs, the trip rod will not be moved. This will result in the stop 4 remaining stationary. What will subsequently result will be as follows: Referring to Fig. 11, the roller on the forked rod 7 is shown as just coming into contact with the step 6^a of the cam 6. This will result in a rapid upward movement of the rod 9 and bell crank 10. At the same time, the stop 4 holding the plate 27 nominally at rest will also maintain the lever 14 in the same position. The dog 21 will not be oscillated on its pivot, as before, hence the stop 13 will come into engagement with the dog 21, and will engage the latter and move the sector 22 upward, owing to the connections between the dog and the sector, to the position shown in Fig. 9. At the same time, the elevation of the dog will raise the limb 20 of the lever 16, engaging the shoulder on the limb 17 with the roller 23, thus exerting stress upon the lever 14. This will move the lever 14 to the left, and, through the agency of the teeth 14^a engaging with the sector 24, will rotate the latter, lifting the lever 26, compressing the spring 30, and moving the plate 27 away from the stop 4. When the upper end of the lever 2 passes the dead center, the expansion of the spring 30 will turn the sector 24 still farther to the right, and will move the lever 14 still farther to the right. The device is now in tripped position, with the sector 22 elevated, as shown in Fig. 9. A further partial rotation of the shaft 5 will lower the forked rod 7, and rod 9, with the lever 10. The sector 22 will be free to be lowered, by the mechanism, which actuates it, but which has not yet been described. The parts will be in the position shown in Fig. 10. The rod 9 will next be manipulated, which will have the effect of moving the lever 10 up and down, but it will have no other effect. The lever 14 will remain to the left, so that the roller 23^a will engage

the shoulder on the limb 17^a at every stroke, raising the dog so that it clears the stop 13.

I will now describe the mechanism which is actuated by the sector 22: This sector engages with a sector 31, which is carried on a rock shaft 32, which lies at right angles to the stub shaft 11. This shaft 32 lies above and at right angles to the transfer cylinder shaft 33. It also lies above and at right angles to a reciprocating and rotating shaft 34. The shaft 32 carries a depending arm 35, provided with a shoe 36 (see Fig. 6). This shoe works in a peripheral groove 37, in a hub 38. Attached to this hub is a spur gear 39. The oscillation of the shaft 32 will, through the agency of the arm 35 and shoe 36, move the gear 39. This gear is secured to the shaft 34, so that it moves with it longitudinally in its bearings. The other end of the shaft 34, on the opposite side of the frame 12, carries the star wheel member 40, of a Geneva stop movement, this member having radial slots 41, and curved lock portions 42.

Referring to Fig. 5, the shaft 33 carries the anchor member of the Geneva stop, such movement member being in the form of a cylinder 43, with a portion of its side cut away at 44. This cylinder carries an arm 45, provided with a roller 46, this roller being opposite to the cut-away portion 44. In addition, the frame 12 is provided with a segmental locking plate 47, which is adapted to enter one of the curved lock portions 42, thereby rigidly locking the star wheel member to the frame. The cylinder 43, carries a cam 48, located opposite to the cut-away portion 44. This cam is adapted to engage with a pin 49, which passes through the frame 12, and carries an arm 50. This arm has a crutch 51, which enters the groove 37 in the hub 38.

The operation of so much of the device, just described, is as follows: The movement of the sector 22, which, as has been described, occurs only after the trip rod 1 has failed to move to the left, will give the shaft 32 a partial rotation. This will slide the shaft 34 through the frame 12, moving the star wheel member 40 of the Geneva stop motion. This moves the star wheel member away from the locking plate 47, permitting the member to be rotated by the engagement of the roller 46 with one of the slots 41, thus rotating the star wheel member through a quarter revolution, and with it, the spur gear 39. When the roller 46 clears the star wheel member, and after the shaft 33 has rotated farther, the rod 49 will be engaged by the cam 48, thus sliding the shaft 34 to its initial position. This will rotate the shaft 32 to its initial position, lowering the sector 22. The sector will remain in this lowered position until the parts are

reset. The rotation of the gear 39 will be transmitted to a gear 51^a, suitably supported on the frame. This gear is connected by means of a pitman 52, to a lever 53 on the bearing box 54 of the shaft 55 which carries the impression cylinder. This box is eccentrically mounted in its bearings, so that the depression of the pitman 52 will move the impression cylinder away from the type cylinder. The gear 51^a is sufficiently wide, so that it will always remain in mesh with the teeth of the spur gear 39. It is also preferably one-half of the diameter of the latter gear, so that it makes one-half a revolution, as the latter gear is given a quarter revolution by the action of the Geneva stop motion. The effect of this is that every time the spur gear is actuated, the gear 51^a will be given a half rotation, and hence the bearings of the impression cylinder will be moved, either away from or toward the type cylinder. It is desirable that the bearings on both ends of the impression cylinder should be simultaneously moved. Therefore, the mechanism is duplicated, so far as is necessary on both sides of the cylinder. This duplicate mechanism is as follows:

The Geneva stop motion, the gears, and pitmen, are duplicated on the other side of the machine as shown in Fig. 3. The connection to this duplicated mechanism is by means of a rod 56 attached to a lever 57 on the shaft 32. The other end of the rod is connected to a lever 58, which carries a sector 59, engaging with a sector 60, on the rock shaft 32^a, which corresponds with the rock shaft 32. The purpose of using the two sectors 59 and 60 is to give the rock shaft 32^a an opposite movement to the rock shaft 32, owing to the reversal of the Geneva stop motion on that side of the machine. To hold the rock shaft 32 in position, a lever 61 is provided, said lever being connected to a rod 62, with a stop 63 thereon and a spring 64. This rod slides in a pivoted saddle 65 (Fig. 4), so that a toggle action is provided. The expansion of the spring 64 will tend to hold the rock shaft 32 in whichever position it is put.

For setting the device, the shaft 32 is provided with a lever 66, which, upon being manipulated, will turn the rock shaft 32 in its bearings, and will move the star wheel member of the Geneva stop motion so that it will be engaged by the roller 46, thus giving the shaft 34 a quarter turn, and the gear 51 a half turn, thus raising the pitman 32, and bringing the impression cylinder into contact with the type cylinder. In addition to this, it is necessary to reset the trip mechanism by moving the sector 24 to its initial position. This is accomplished by means of a crank 67. The shafts 5 and 33 being connected together by gearing, will revolve in sequence, and will both turn so

long as the press is in operation. These shafts, or a portion of them, constitute therefore a constantly moving device.

While I have shown the cam 6, as associated with the shaft 5, it is apparent that it need not be connected directly to this portion of the constantly moving device. For the same reason, I have shown the Geneva stop motion as driven directly from the shaft 33, but it is equally apparent that it need not be driven by this portion of the constantly moving device.

I have described my invention in connection with the particular magnetic rectifying, gaging and alining device, but it is to be understood that such description is solely for purposes of illustration, and that any other device which contains an element which moves in response to the passage of a properly alined and gaged sheet, may be employed, without departing from the invention. I have also illustrated my invention in connection with a tripping device of certain type, but it is to be understood that the details of this tripping device may be varied as desired, without departing from the invention.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:—

1. In a printing press, the combination of a constantly moving member, a cam rotated by such member; a device, which contains an element which moves in response to the passage of a properly alined and gaged sheet; a movable stop, connected to the element so that it will move in response to the movement of the element; a lever swinging in the path of the stop; a toothed sector, associated with the lever; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop, on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting means.

2. In a printing press, the combination of a constantly moving member; a cam rotated by such member; a device which contains an element which moves in response to the passage of a properly alined and gaged sheet; a movable stop connected to the element so that it will move in response to the movement of the element; a lever swinging in the path of the stop; a toothed sector, associated with the lever; a spring pressed rod, exerting stress upon the lever, on one side of the axis thereof; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting means.

3. In a printing press, the combination of a constantly moving member; a cam rotated by such member; a device which contains an element which moves in response to the passage of a properly alined and gaged sheet; a movable stop, connected to the element so that it will move in response to the movement of the element; a lever swinging in the path of the stop; a toothed sector, associated with the lever; a second lever, having a toothed sector in engagement with the first named sector; a pivot for such lever; stops on the lever, on opposite sides of the pivot; a member straddling the pivot and engaging with the stops; a spring for elastically engaging the member with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting means.

4. In a printing press, the combination of a constantly moving member; a cam rotated by such member; a device which contains an element which moves in response to the passage of a properly alined and gaged sheet; a movable stop, connected to the element so

that it will move in response to the movement of the element; a lever swinging in the path of the stop; a toothed sector, associated with the lever; a spring pressed rod, exerting stress upon the lever, on one side of the axis thereof; a second lever, having a toothed sector in engagement with the first named sector; a pivot for such lever; stops on the lever, on opposite sides of the pivot; 5 a member straddling the pivot and engaging with the stops; a spring, for elastically engaging the member with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 10 means.

5. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; a toothed sector, associated with the lever; means, exerting stress upon the lever, on one side of the axis thereof; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 15 means.

6. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; a toothed sector, associated with the lever; means exerting stress upon the lever, on one side of the axis thereof; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 20 means.

stress upon the lever, on one side of the axis thereof; a second lever, having a toothed sector in engagement with the first named sector; a pivot for such lever; stops on the lever, on opposite sides of the pivot; a member straddling the pivot and engaging with the stops; a spring, for elastically engaging the member with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 25 means.

7. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; means, associated with the lever; means exerting stress upon the lever, on one side of the axis thereof; a second lever, having means in engagement with the first named means; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 30 means.

8. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; means associated with the lever; means exerting stress upon the lever, on one side of the axis thereof; a second lever, having means in engagement with the first named means; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a printing couple, comprising type and impression cylinders; a shaft; connecting means to the impression cylinder, actuated by the movement of the said shaft; and movable supports for the impression cylinder, said supports being connected to the connecting 35 means.

5 pivot and engaging with the stops; a third lever turning around the same pivot; a dog, pivoted to said lever; connections between the dog and the straddling member; a device 10 turning around the same pivot; a stop on the device, in the path of the dog; means connecting the cam with the device; a printing couple, comprising type and impression cylinders; a shaft; connecting means to the 15 impression cylinder, actuated by the movement of the said shaft; and movable supports for the impression cylinder, said supports being connected to the connecting means.

15 9. In a printing press, the combination of a constantly moving member; a cam rotated by such member; a device which contains an element which moves in response to the passage of a properly aligned and 20 gaged sheet; a movable stop connected to the element so that it will move in response to the movement of the element; a lever swinging in the path of the stop; means, associated with the lever; means exerting 25 stress upon the lever, on one side of the axis thereof; a second lever, having means in engagement with the first named means; a pivot for such lever; stops on the lever, on opposite sides of the pivot; a member 30 straddling the pivot and engaging with the stops; a spring for elastically engaging the member with the stops; a third lever turning around the same pivot; a dog, pivoted to said lever; connections between 35 the dog and the straddling member; a device turning around the same pivot; a stop on the device, in the path of the dog; means connecting the cam with the device; a printing couple, comprising type and 40 impression cylinders; a shaft; connecting means to the impression cylinder, actuated by the movement of the said shaft; and movable supports for the impression cylinder, said supports being connected to the connecting means.

45 10. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; a toothed sector, associated with the lever; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog;

means connecting the cam with the device; a shaft; connections between the shaft and the lever which carries the dog; a second shaft, at right angles to the first shaft; a Geneva stop movement, having a star wheel 70 member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a printing couple, comprising type and impression cylinders; connecting means to the 80 impression cylinder, actuated by the movement of the second shaft; and movable supports for the impression cylinder, said supports being connected to the connecting means.

85 11. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; a toothed sector, associated with the lever; a spring 90 pressed rod, exerting stress upon the lever, on one side of the axis thereof; a second lever, having a toothed sector in engagement with the first named sector; a pivot for such lever; stops on the lever, on opposite sides 95 of the pivot; a member straddling the pivot and engaging with the stops; a third lever turning around the same pivot; a dog, pivoted to said lever; connections between the dog and the straddling member; a device 100 turning around the same pivot; a stop on the device, in the path of the dog; means connecting the cam with the device; a shaft; connections between the shaft and the lever which carries the dog; a second shaft, at right angles to the first shaft; a Geneva stop movement, having a star wheel member and an anchor member, the star wheel member being carried by the second shaft, said second shaft sliding in its bearings; means connecting the first shaft to the 110 second shaft, for sliding the latter; connections between the anchor member of the Geneva stop movement and the constantly moving member, for rotating the former; a printing couple, comprising type and impression cylinders; connecting means to the 115 impression cylinder, actuated by the movement of the second shaft; and movable supports for the impression cylinder, said supports being connected to the connecting means.

120 12. In a printing press, the combination of a constantly moving member; a cam rotated by such member; a device which contains an element which moves in response to the passage of a properly aligned and gaged sheet; a movable stop connected to the element so that it will move in response to the movement of the element; a lever swinging in the path of the stop; a toothed sector, associated with the lever; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog;

125 65 means connecting the cam with the device; a shaft; connections between the shaft and the lever which carries the dog; a second shaft, at right angles to the first shaft; a Geneva stop movement, having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a printing couple, comprising type and impression cylinders; connecting means to the 130 impression cylinder, actuated by the movement of the second shaft; and movable supports for the impression cylinder, said supports being connected to the connecting means.

tains an element which moves in response to the passage of a properly alined and gaged sheet; a movable stop connected to the element so that it will move in response to the movement of the element; a lever swinging in the path of the stop; means associated with the lever; a second lever, having means in engagement with the first named means; a pivot for such lever; stops 10 on the lever, on opposite sides of the pivot; a member straddling the pivot and engaging with the stops; a third lever turning around the same pivot; a dog, pivoted to said lever; connections between the dog and the straddling member; a device turning around the same pivot; a stop on the device, in the path of the dog; means connecting the cam with the device; a shaft; connections between the shaft and the lever which carries the dog; 15 a second shaft, at right angles to the first shaft; a Geneva stop movement, having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a 20 printing couple, comprising type and impression cylinders; connecting means to the impression cylinder, actuated by the movement of the second shaft; and movable supports for the impression cylinder, said supports being connected to the connecting means.

13. In a printing press, the combination of a constantly moving member; a cam rotated by such member; a device which contains an element which moves in response to the passage of a properly alined and gaged sheet; a movable stop connected to the element so that it will move in response to the movement of the element; a lever swinging 25 in the path of the stop; a toothed sector, associated with the lever; means exerting stress upon the lever, on one side of the axis thereof; a second lever, having a toothed sector in engagement with the first named sector; a pivot for such lever; stops on the lever, on opposite sides of the pivot; a member straddling the pivot and engaging with the stops; a third lever turning around the same pivot; a dog, pivoted to the said lever; connections between the dog and the straddling member; a device turning around the same pivot; a stop on the device, in the path of the dog; means connecting the cam with the device; a shaft; connections between the shaft and the lever which carries the dog; a second shaft, at right angles to the first shaft; a Geneva stop movement, having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a printing couple, comprising type and impression cylinders; connecting means to the impression cylinder, actuated by the movement of the second shaft; and movable supports for the impression cylinder, said supports being connected to the connecting means.

15. In a printing press, the combination of a constantly moving member; a cam rotated by such member; a device which contains an element which moves in response to the passage of a properly alined and gaged sheet; a movable stop connected to the element so that it will move in response to the movement of the element; a lever swinging in the path of the stop; means associated with the lever; means exerting stress upon the lever, on one side of the axis thereof; a second lever, having means in engagement with the first named means; a pivot for such lever; stops on the lever, on opposite sides of the pivot; a member straddling the pivot and engaging with the stops; a third lever turning around the same pivot; a dog, pivoted to the said lever; connections between the dog and the straddling member; a device turning around the same pivot; a stop on the device, in the path of the dog; means connecting the cam with the device; a shaft; connections between the shaft and the lever which carries the dog; a second shaft, at right angles to the first shaft; a Geneva stop movement, having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a printing couple, comprising type and impression cylinders; connecting means to the impression cylinder, actuated by the movement of the second shaft; and movable supports for the impression cylinder, said supports being connected to the connecting means.

a pivot for such lever; stops on the lever, on opposite sides of the pivot; a member straddling the pivot and engaging with the stops; a third lever turning around the same 5 pivot; a dog, pivoted to said lever; connections between the dog and the straddling member; a device turning around the same pivot; a stop on the device, in the path of the dog; means connecting the cam with the 10 device; a shaft; connections between the shaft and the lever which carries the dog; a second shaft, at right angles to the first shaft; a Geneva stop movement, having a star wheel member and an anchor member, 15 the star wheel member being carried by the second shaft, said second shaft sliding in its bearings; means connecting the first shaft to the second shaft, for sliding the latter; connections between the anchor mem- 20 ber of the Geneva movement and the constantly moving member, for rotating the former; a printing couple, comprising type and impression cylinders; connecting means to the impression cylinder, actuated by the 25 movement of the second shaft; and movable supports for the impression cylinder, said supports being connected to the connecting means.

16. In a printing press, the combination 30 of a constantly moving member; a cam rotated by such member; a device which contains an element which moves in response to the passage of a properly alined and gaged sheet; a movable stop connected to 35 the element so that it will move in response to the movement of the element; a lever swinging in the path of the stop; a toothed sector, associated with the lever; a second lever, having a toothed sector in engagement 40 with the first named sector; a pivot for such lever; stops on the lever, on opposite sides of the pivot; a member straddling the pivot and engaging with the stops; a third lever turning around the same pivot; a dog, piv- 45 oted to said lever; connections between the dog and the straddling member; a device turning around the same pivot; a stop on the device, in the path of the dog; means connecting the cam with the device; a shaft; 50 connections between the shaft and the lever which carries the dog; a second shaft, at right angles to the first shaft; a Geneva stop movement, having a star wheel member and an anchor member, the star wheel member 55 being carried by the second shaft, said sec- 60 ond shaft sliding in its bearings; means connecting the first shaft to the second shaft, for sliding the latter; connections between the anchor member of the Geneva move- 65 ment and the constantly moving member, for rotating the former; a cam, carried by said anchor member; a rod slidably mounted to be engaged by the cam; means connect- 70 ing the rod with the second shaft, to retract the latter to its normal position; a printing 75 couple, comprising type and impression cylinders; connecting means to the impression cylinder, actuated by the movement of the second shaft; and movable supports for the impression cylinder, said supports being connected to the connecting means.

17. In a printing press, the combination 80 of a constantly moving member; a cam rotated by such member; a device which contains an element which moves in response to the passage of a properly alined and gaged sheet; a movable stop connected to the element so that it will move in response to the movement of the element; a lever swinging in the path of the stop; a toothed sector, associated with the lever; a second lever, having a toothed sector in engagement 85 with the first sector; a pivot for such lever; stops on the lever, on opposite sides of the pivot; a member straddling the pivot and engaging with the stops; a third lever turning around the same pivot; a dog, pivoted to said lever; connections between the dog and the straddling member; a device turning around the same pivot; a stop 90 on the device, in the path of the dog; means connecting the cam with the device; a shaft; connections between the shaft and the lever which carries the dog; a second shaft, at right angles to the first shaft; a Geneva stop 95 movement, having a star wheel member and an anchor member, the star wheel member being carried by the second shaft, said second shaft sliding in its bearings; means connecting the first shaft to the second 100 shaft, for sliding the latter; connections between the anchor member of the Geneva movement and the constantly moving member, for rotating the former; a gear wheel, carried by the second shaft; a second gear 105 wheel, engaging with the said first gear wheel; a printing couple, comprising type and impression cylinders; connecting means to the impression cylinder, actuated by the movement of the second shaft; and movable 110 supports for the impression cylinder, said supports being connected to the connecting means.

18. In a printing press, the combination 115 of a constantly moving member; a cam rotated by such member; a device which contains an element which moves in response to the passage of a properly alined and gaged sheet; a movable stop connected to the element so that it will move in response to the movement of the element; a lever swinging in the path of the stop; a toothed sector, associated with the lever; a second lever, having a toothed sector in engagement 120 with the first named sector; a pivot for such lever; stops on the lever, on opposite sides of the pivot; a member straddling the pivot and engaging with the stops; a third lever turning around the same pivot; a dog, pivoted to said lever; connections 125

130

- between the dog and the straddling member; a device turning around the same pivot; a stop on the device, in the path of the dog; means connecting the cam with the device; a 5 shaft; connections between the shaft and the lever which carries the dog; a second shaft, at right angles to the first shaft; a Geneva stop movement, having a star wheel member and an anchor member, the star wheel member being carried by the second shaft, said second shaft sliding in its bearings; means connecting the first shaft to the second shaft, for sliding the latter; connections between the anchor member of the Geneva movement 10 and the constantly moving member, for rotating the former; a printing couple, comprising type and impression cylinders; connecting means to the impression cylinder, actuated by the movement of the second shaft; movable supports for the impression cylinder, said supports being connected to the connecting means, the said Geneva stop movement being duplicated on both sides of the printing couple; and means connecting 15 the first shaft of one side with the equivalent shaft on the other side.
19. In a printing press, the combination of a constantly moving member; a cam rotated by such member; a device which 20 contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to 25 move; a shaft; connections between the trip device and the shaft, for moving the latter; a second shaft, at right angles to the first shaft; a Geneva stop movement having a star wheel member and an anchor member, 30 the star wheel member being carried by the second shaft, said second shaft sliding in its bearings; means connecting the first shaft to the second shaft, for sliding the latter; connections between the anchor member of the Geneva movement and the constantly moving member, for rotating the former; a cam, carried by said anchor member; a rod slidably mounted to be engaged by the cam; means connecting the rod with the second shaft, to retract the latter to its normal position; a printing couple, comprising type and impression cylinders; connecting means to the impression cylinder, actuated by the movement of the second shaft; and movable supports for the impression cylinder, said supports being connected to the connecting means.
21. In a printing press, the combination of a constantly moving member; a cam rotated by such member; a device which 35 contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to 40 move; a shaft; connections between the trip device and the shaft, for moving the latter; a second shaft, at right angles to the first shaft; a Geneva stop movement having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a gear wheel, carried by the second shaft; a second gear wheel, 45 engaging with the said first gear wheel; a printing couple, comprising type and impression cylinders; connecting means to the impression cylinder, actuated by the movement of the second gear wheel; and movable supports for the impression cylinder, said supports being connected to the connecting means.
20. In a printing press, the combination of a constantly moving member; a cam rotated by such member; a device which 50 contains an element which moves in response to the passage of a properly aligned and gaged sheet; a movable stop connected to the element so that it will move in response to the movement of the second gear wheel; and movable supports for the impression cylinder, said supports being connected to the connecting means.
22. In a printing press, the combination of a constantly moving member; a cam 55

rotated by such member; a device which contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to move; a shaft; connections between the trip device and the shaft, for moving the latter; a second shaft, at right angles to the first shaft; a Geneva stop movement having a star wheel member and an anchor member, the star wheel member being carried in the second shaft, said second shaft sliding in its bearings; means connecting the first shaft to the second shaft, for sliding the latter; connections between the anchor member of the Geneva movement and the constantly moving member, for rotating the former; a cam, carried by said anchor member; a rod slidably mounted to be engaged by the cam; means connecting the rod with the second shaft, to retract the latter to its normal position; a printing couple, comprising type and impression cylinders; connecting means to the impression cylinder, actuated by the movement of the second shaft; and movable supports for the impression cylinder, said supports being connected to the connecting means.

23. In a printing press, the combination of a constantly moving member; a cam rotated by such member; a device which contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to move; a shaft; connections between the trip device and the shaft, for moving the latter; a second shaft, at right angles to the first shaft; a Geneva stop movement having a star wheel member and an anchor member, the star wheel member being carried by the second shaft, said second shaft sliding in its bearings; means connecting the first shaft to the second shaft, for sliding the latter; connections between the anchor member of the Geneva movement and the constantly moving member, for rotating the former; a printing couple, comprising type and impression cylinders; connecting means to the impression cylinder, actuated by the movement of the second shaft; and movable supports for the impression cylinder, said supports being connected to the connecting means.

means; the said Geneva stop movement being duplicated on both sides of the printing couple; and means connecting the first shaft of one side with the equivalent shaft on the other side. 70

24. In a printing press, the combination of a constantly moving member; a cam rotated by such member; a device which contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to move; a shaft; connections between the trip device and the shaft, for moving the latter; a second shaft, at right angles to the first shaft; a Geneva stop movement having a star wheel member and an anchor member, the star wheel member being carried by the second shaft, said second shaft sliding in its bearings; means connecting the first shaft to the second shaft, for sliding the latter; connections between the anchor member the Geneva movement and the constantly moving member, for rotating the former; a cam, carried by said anchor member; a rod slidably mounted to be engaged by the cam; means connecting the rod with the second shaft, to retract the latter to its normal position; a printing couple; comprising type and impression cylinders; connecting means to the impression cylinder, actuated by the movement of the second shaft; movable supports for the impression cylinder, said supports being connected to the connecting means; the said Geneva stop movement being duplicated on both sides of the printing couple; and means connecting the first shaft of one side with the equivalent shaft on the other side. 100 110 115

25. In a printing press, the combination of a constantly moving member; a cam rotated by such member; a device which contains an element which moves in response to the passage of a properly aligned and gaged sheet; a movable stop connected to the element so that it will move in response to the movement of the element; a trip device, which has a member swinging in the path of the stop, and a member moved by the cam, said device containing means which locks the parts when the stop moves, and trips the device when the stop fails to move; a shaft; connections between the trip device and the shaft, for moving the latter; a second shaft, at right angles to the first shaft; a Geneva stop movement having a star wheel member and an anchor member, the star wheel member being carried by the second shaft, said second shaft sliding in its 120 125 130

bearings; means connecting the first shaft to the second shaft, for sliding the latter; connections between the anchor member of the Geneva movement and the constantly moving member, for rotating the former; a gear wheel, carried by the second shaft; a second gear wheel, engaging with the said first gear wheel; a printing couple, comprising type and impression cylinders; connecting means to the impression cylinder, actuated by the movement of the second gear wheel; movable supports for the impression

cylinder, said supports being connected to the connecting means; the said Geneva stop movement being duplicated on both sides 15 of the printing couple; and means connecting the first shaft of one side with the equivalent shaft on the other side.

This specification signed and witnessed this 25th day of October, 1912.
